No. 792,177.

PATENTED JUNE 13, 1905.

W. J. SUMNER.

POWER DRIVEN TROLLEY HEAD.

APPLICATION FILED NOV. 14, 1904.

UNITED STATES PATENT OFFICE.

WILLIAM J. SUMNER, OF HOLYOKE, MASSACHUSETTS, ASSIGNOR TO THE COBURN TROLLEY TRACK MANUFACTURING COMPANY, OF WILLIAMSETT, MASSACHUSETTS, A CORPORATION.

POWER-DRIVEN TROLLEY-HEAD.

SPECIFICATION forming part of Letters Patent No. 792,177, dated June 13, 1905.

Application filed November 14, 1904. Serial No. 232,676.

To all whom it may concern:

Be it known that I, WILLIAM J. SUMNER, a citizen of the United States of America, residing at Holyoke, in the county of Hampden and 5 State of Massachusetts, have invented new and useful Improvements in Power-Driven Trolley-Heads, of which the following is a specification.

This invention relates to trolleys employed 10 in connection with an overhead track, and has special reference to improved power-driven trolley-heads for use in a track of the character above described, the object thereof being to provide a construction of trolley-head 15 adapted to be driven by power from a motor suspended from the trolley-head independently of the traction effect of the wheels bearing 20 on the track; and the invention consists in the construction described in the following specification and pointed out in the claims.

In the drawings forming part of this application, Figure 1 is a side elevation of a trolley-head to which the invention has been applied, the track and the rack supported 25 above it being shown in longitudinal section. Fig. 2 is a sectional elevation on line 2-2, Fig. 1.

Referring now to the drawings, the track (indicated by *a*) is shown in Fig. 2 as made up of 30 two independent longitudinally-disposed sections according to a well-known manner to constitute a suitable overhead track, each of the sections thereof having an inturned lower edge constituting the tread portion of the 35 track, said track-sections being supported in brackets *b*, located at suitable intervals along the track and screwed up against suitable supporting-beams. Provision is made in each bracket to receive a rack *c*, which is located 40 centrally between the two depending arms of the brackets and may be secured thereto by bolts or otherwise in substantially the same plane as the track-slot *d* between the two sections of the track.

45 The track construction constitutes no part of this invention, and some other form of track may be substituted therefor, if desired, which will permit the operation therein of the

hereinafter-described trolley-head in connection with the rack *c*.

The trolley-head is supported on two pairs 50 of wheels *e* and *e'*, which are secured to the outer extremities of two axles *f* and *f'*, which are supported in the upper ends *g* of two arms *h*, which depend below said wheels and 55 extend through the track-slot *d*. From a point near the lower end of the shaft these arms are made round in cross-section and their lower ends are threaded to receive the nuts *j*, together with a suitable check-nut, 60 these lower ends extending loosely through the ends of a yoke *k*. These extremities of the yoke are chambered out on the under side thereof to receive a suitable ball-bearing *m*, (shown only in dotted lines in Fig. 1,) to the 65 end that whatever may be the weight suspended from said yoke the arms *h* may freely rotate more or less on their longitudinal axes, whereby when the trolley-head passes around a piece of curved track the wheels may adapt 70 themselves to the curvature thereof. It is unnecessary to describe here the nature of the bearing construction in which the axles *f* rotate, it being sufficient to say that it is preferably a roller-bearing so constructed that 75 said shaft will turn on the rolls *n*. (Shown in dotted lines in Fig. 1.)

On the yoke a vertically-disposed frame is constructed, which extends up through the track-slot *d*, and it consists of the two uprights *p*, whose upper ends are connected together by two flat bars *q*, firmly secured one to each side at the upper end of these uprights. The latter are provided with a broad base portion *r*, rectangular in cross-section, through 80 which the arms *h* extend and in which they fit loosely, and uniting the lower ends of these two uprights are two other flat bars *s*, each secured to opposite sides of said lower portions *r*.

On a shaft *t* between the bars *q* is located a 85 gear *v*, the teeth of which mesh with the teeth of the rack *c* above it and also with the teeth of another gear *w* below it, which last-named gear is supported between the flat bars *s* on a shaft *x*, the extremities of which shaft extend through two bushings *z* in the bars *s*,

whose inner ends are provided with a head, over the outer ends of which the nuts 4 are fitted, whereby these bushings may be clamped to said bars to constitute proper bearings for 5 the shaft. The gear w is keyed to this shaft, and on the outer extremities of the latter sprocket-wheels 5 are keyed, over which chains 6 run to some suitable motor, which may be supported on a platform (not shown) which 10 is suspended from a horizontally-disposed rod 7, which extends through swiveled supports 8, pivotally connected with the yoke k by a bolt 9. The swiveled connection 8, through which the rod 7 passes, is arranged, 15 as shown in Fig. 2, to swing on a vertical axis, and to render this swinging movement as free as possible this connection is provided also with a ball-bearing 10, which bearing is embraced by a two-part supporting member 20 12, the two halves of which depend from the bolt 9, which passes through the yoke k . By means of this latter connection with the yoke it is clear that the swiveled connection 8 may also swing on the bolt 9, as well as rotate on its 25 own vertical axis, and as the rod 7 passes freely through this swiveled connection 8 the motor-platform, which is supported on straps 14, depending from the rod 7, may swing in any direction more or less freely, whereby no 30 strain may be put upon the trolley-head when the latter is passing around a curve. In practice the straps 14 would of course be located each side of the supports of the rod 7.

It is of course immaterial what type of motor is employed, and it has not been deemed necessary to show any motor or platform herein. Preferably, however, an electric motor would be employed, and it would lie within the province of any one skilled in the art 40 to establish such a motor and platform and connect therewith a chain or chains 6, whereby the gear w may be rotated in either direction to drive the trolley-head.

This particular form of traction device is 45 especially adapted to be used in many places, as in mills and factories where it is necessary to make frequent shifts of heavy material, as the track and the trolley-head may be adapted to curves of a short radius, and the track 50 is capable of being provided with switches and branches. This form of power-driven trolley-head is also particularly adapted to be used for carrying material up an incline where the traction effect of the wheels alone would 55 be unequal to the task were the wheels rotated directly from the gear w , as described in another application filed by me concur-

rently herewith, instead of being provided with the rack c , with which the driving-gears are directly connected.

In practice any platform suspended from the rod 7 would be supported ordinarily by a trolley-head such as is shown in Fig. 1 in one end and by a similar trolley-head minus the gears v and w at the other end, or, if desired, 60 two heads such as described herein and similarly driven may be used. Such a platform with its motor provides traction-power sufficient for all ordinary uses, to which may be attached trailers consisting of other platforms 70 running on the track a and drawn by the motor.

Having thus described my invention, what I claim, and desire to secure by Letters Patent of the United States, is—

1. The combination with an overhead-trolley track, of a trolley-head thereon comprising wheels to bear on the track, supports for said wheels rotatable on an axis vertical to the track, a rack supported above the track, a gear 80 on the trolley-head, to mesh with the rack, and means to rotate said gear.

2. The combination with an overhead-trolley track comprising two parallel track portions having a track-slot between them, of a 85 trolley-head to run on said tracks, a rack supported above the track, a gear supported on the trolley-head in mesh with said rack, said gear being located between said two track portions.

3. The combination with an overhead-trolley track comprising two parallel track portions having a track-slot between them, of a trolley-head comprising wheels to run on said track portions, arms having bearings in the 95 upper ends thereof for said wheels, the lower ends of the arms depending through said track-slot, a rigid connecting member between said arms, and a gear supported on said member in the plane of the track-slot, and extending 100 into the latter, a rack located in operative relation to said gear with which the latter engages, and means to rotate said gear.

4. A tubular overhead-trolley track, a trolley-head suspended from the track and comprising wheels to run in said track; a rack in said tubular track, a gear supported on the trolley-head to engage said rack, and means on the head located outside the track to impart rotary movements to said gear.

WILLIAM J. SUMNER.
